UNITED STATES PATENT OFFICE.

JASPER EDISON HORNER AND GEORGE BARNARD WOLF, OF TOLEDO, OHIO.

CROSSING PROTECTOR.

Application filed May 16, 1924. Serial No. 713,797.

To all whom it may concern:

Be it known that we, JASPER EDISON HORNER and GEORGE BARNARD WOLF, citizens of the United States, residing at Toledo, in 5 the county of Lucas and State of Ohio, have invented new and useful Improvements in Crossing Protectors, of which the following is a specification.

This invention relates to a crossing 10 protector for railroads, the general object of the invention being to provide automatic means for lowering gates or other barriers upon the approach of a train and to remove the barriers after the train passes the crossing.

15 This invention also consists in certain other features of construction and in the combination and arrangement of the several parts, to be hereinafter fully described, illustrated in the accompanying drawings and 20 specifically pointed out in the appended claims.

In describing the invention in detail, reference will be had to the accompanying drawings wherein like characters denote like 25 or corresponding parts throughout the several views, and in which:—

Figure 1 is a side view of a railroad track and crossing showing the invention in use.

Figure 2 is a plan view.

30 Figure 3 is a section on line 3—3 of Figure 2.

Figure 4 is a section on line 4—4 of Figure 2.

Figures 5, 6 and 7 are detail views.

35 In these views, A indicates the track and B the crossing. In carrying out our invention we arrange gates 1 at the crossing which are pivoted to the posts 2 and which are normally held in raised position by the 40 weights 3. A latch 4 is arranged for holding each gate in lowered position after the gates have been lowered, this latch being so arranged that it will be struck by a train as the train is passing the crossing so that

45 the latch will be moved to releasing position to permit the weights to raise the gates. This latch is so formed that its upper end will pass under the weighted end of the gate when the same is lowered so as to prevent the return or opening movement of the gate, the latch being spring impelled. The

50 other end of the latch will then be in a position close to the one of the rails of the track where it will be struck and depressed by the wheels of a train, this depression causing the latch to swing out from under the gate

and thus permit the weight to raise the gate. A pedal lever 5 is arranged adjacent one rail of the track a distance from the crossing so that it will be depressed by the wheels 60 of a train. This pedal lever engages a second lever 6 which is pivoted intermediate its ends as at 7 and has its other end connected by a link 8 with a third lever 9 which is pivoted intermediate its ends to the support 10. The other end of this lever 9 is attached to a chain 11 which passes over a pulley 12 on a post 13 and the other end of the cable is connected with a gate, as shown at 14, in such a manner that when the pedal 65 lever 5 is depressed the cable will be pulled upon to move the gates to lowered position and thus prevent a vehicle or pedestrian from passing over the track at the crossing. The latch 4 will hold the gates in lowered 70 position until the train reaches the crossing when a part on the train will strike the latch and release the same so that the weights can raise the gates so that the crossing will be free after a train passes over the same. 75 The cable passes over suitable guiding pulleys 15 which are suitably supported.

80 From the foregoing it will be seen that we have provided simple and effective means whereby a train may automatically lower the gates before the train reaches the crossing and will actuate the latch means for permitting the gates to raise again as the train passes the crossing.

85 If desired, a lamp 16 can be used on each gate and an alarm 17 can also be provided, the circuit of which is closed by the approach of a train so that persons will be warned that the gates are about to be lowered and thus be prevented from being caught between the gates at the crossing.

90 It is thought from the foregoing description that the advantages and novel features of the invention will be readily apparent.

95 We desire it to be understood that we 100 may make changes in the construction and in the combination and arrangement of the several parts, provided that such changes fall within the scope of the appended claim.

105 What we claim is:—

Railroad crossing protecting means comprising gates, weighted means for holding the gates in raised position, a spring pressed latch member having its upper end adapted to pass under the weighted end of a gate 110 when the gate is lowered to prevent the weight from opening the gate again, the

other end of the latch member extending to a point close to one of the rails of the track so that it will be struck and depressed by a wheel of the train which moves the latch member to releasing position, a pedal lever adjacent the track adapted to be depressed by the passage of a train over the same, a system of levers actuated by the

pedal lever, flexible means for connecting the system to the gates and guiding means for the flexible means.

In testimony whereof we affix our signatures.

JASPER EDISON HORNER.
GEORGE BARNARD WOLF.
